PAD BOX

Charles K. Woodman, Beverly, Mass., assignor to
 United Shoe Machinery Corporation, Flemington, N. J., a corporation of New Jersey

Application June 25, 1949, Serial No. 101,338

10 Claims. (Cl. 12—38)

1

This invention relates to apparatus for operating on shoes and more particularly to pad boxes used in applying pressure to shoe bottoms.

It is an object of the invention to provide an improved pad box construction in which the pressure applying surface of the pad box readily conforms to the longitudinal contour of the shoe bottom without the necessity of making any manual adjustments for shoes of different heel heights.

To this end and in accordance with a feature of the invention the shoe supporting pad is carried by heel, shank and forepart supporting members which are pivotally connected and are mounted for relative adjustments in response to the pressure of a shoe against the pad. As illustrated, the heel supporting member is mounted for heightwise movement and the shank and forepart supporting members are mounted for tipping movements to conform to the longitudinal contour of the shoe bottom.

In accordance with a further feature of the invention the pressure is transmitted through the supporting members to the shoe by a resilient pad capable of readily assuming the contour of the supporting members and of the shoe bottom without offering appreciable resistance to the adjustment of the supporting members in response to pressure applied to the shoe bottom. As illustrated herein the pad is formed of a plurality of sheets of rubber capable of sliding with respect to one another in the adjustment of the supporting members, the sheets having spaced parallel ribs on opposite faces, the ribs on the lower faces extending in one direction and the ribs on the upper faces extending in a direction at right angles to the ribs on the lower faces.

The pad is illustrated herein as covered by a flexible steel blanket which is relatively stiff transversely of the pad and is arranged to distribute the maximum pressure around the margin of the shoe bottom. In accordance with a still further feature of the invention the flexible steel blanket comprises a plurality of transversely extending rods carried at their ends by longitudinally extending flexible cables permitting the blanket to yield readily in accordance with the longitudinal contour of the shoe bottom, these rods extending throughout that portion of the pad which underlies the shank and a portion of the forepart of the shoe, the toe end of the shoe resting on a plurality of stiff metal plates which are radially arranged to afford the proper pressure distribution around the toe end of the shoe.

To confine the sides of the pad and in accord-

2

ance with another feature of the invention, the pad-supporting members have associated therewith side walls which, in order to facilitate relative tipping movements of the shank and forepart supporting members, are articulate in construction.

The above and other features of the invention including various details of construction and novel combinations of parts will now be described 10 by reference to the drawings and pointed out in the claims.

In the drawings,

Fig. 1 is a side elevation, partly in section, of one form of pad box in which the invention 15 is embodied; and

Fig. 2 is a plan view, partly in section, of the pad box.

The pad box is carried by a supporting frame consisting of a pair of side plates 10 connected 20 by a bottom plate 12 (Fig. 1). The side plates are pivoted at 14 on supporting posts 16, this arrangement permitting the pad box to swing bodily with the side plates if necessary to insure proper distribution of pressure to a shoe S through toe and heel abutments 18, 20.

The rear portions or left ends of the side plates 10, as viewed in the drawings, carry inwardly extending pins 22 on which are pivoted bell crank levers 24 which are in turn connected by pins 26 to the rear end of a supporting member 28 for the heel portion of a pad. The heel supporting member 28 is pivoted at its forward end by a pin 30 to a shank supporting member or plate 32 the forward portion of which is in turn pivotally connected by a pin 34 to a forepart supporting member or plate 36. The shank supporting plate 32 is pivotally carried by the side plates 10 on pins 38 which also form fulcrums for gear segments 40 having rearwardly extending arms 42 pivotally connected to the forward end of the heel supporting member 28 by extensions of the pivot pin 30.

The gear segments 40 also have downwardly extending arms 44 which are connected by links 46 to the lower ends of the bell crank levers 24 so that the heel supporting member is carried by a parallel linkage arrangement for vertical movement to accommodate shoes of different heel heights. The pin 34 which connects the shank and forepart supporting members 32, 36 extends laterally beyond the forepart supporting member 36 and passes through the gear segments 40. These gear segments mesh with gear segments 48 which are fulcrumed on pins 50 carried 55 by the side plates 10. The gear segments 48 have

forwardly extending arms 52 which carry pins 54 arranged to enter slots 56 in the forward or right end of the forepart supporting member 36 providing lost motion connections between the segments and the forepart supporting members. By this arrangement if the heel supporting member 28 is pushed downwardly the shank supporting plate 32 will pivot in a counterclockwise direction, this movement acting through the gear segments 40, 48 to cause pivotal movement of the forepart supporting member 36 in a clockwise direction about the pin 34. Conversely if the rear end of the forepart supporting member is moved downwardly the shank supporting member is moved in a clockwise direction about the pivot 38 and the heel supporting member 28 moves upwardly. The gear ratios between the segments 40, 48 which control the movements of the shank and forepart supporting members are such that the correct relationship between the heel, shank and forepart supporting members is maintained for lasts of different heel heights, it being understood that the amount of toe spring of different lasts is not in direct proportion to the heel heights.

Carried by the heel, shank and forepart supporting members are a plurality of layers of rubber sheets 58 each of which sheets is provided on one face with spaced ribs 66 extending transversely of the pad box, the other face of each of the sheets being provided with similarly spaced ribs 61 extending lengthwise of the pad box. These layers of rubber sheets form a rubber pad member having flow characteristics similar to that of a water bag commonly employed in pad boxes for cement attachment of outsoles to shoe bottoms. A pad member of the type shown herein is illustrated and described in greater detail in Letters Patent of the United States No. 2,584,313, granted February 5, 1952, on an application filed in my name. A pad member formed in this manner offers little resistance to adjustment for shoes of different heel heights because of the ease with which the sheets of rubber can slide lengthwise with respect to one another in the adjustment of the pad box.

The heel supporting member 28 includes vertical walls 62 providing a U-shaped box-like structure in which the heel ends of the rubber sheets 58 are received. Carried by the pin 34 near its outer ends are vertical links 64 the rearward faces of which, considering the toe end of the pad box as the front, have formed therein vertically extending grooves 66 to receive the forward ends of rods 68 the rearward ends of which are received in vertical grooves 70 in the adjacent ends of the walls 62. The upper ends of the links 64 are connected to the upper forward portions of the walls 62 by links 72 and pins 74, 76. The links 72 are also connected to the side plates 10 by pins 78. The rods 68 with the shank supporting plate 32 and the links 72 form an articulate structure for confining those portions of the rubber sheets 58 which underlie the shank portion of the shoe.

The links 64 have formed in their front faces vertically extending grooves 80 to receive the ends of U-shaped rods 82 which cooperate with the forepart supporting plate 36 to form an articulate enclosure for the forepart portions of the rubber sheets 58. Links 84 connected at 86 to the edges of the forepart supporting plate 36 extend upwardly and maintain the rods 62 against lateral displacement, longitudinal displacement of the rods being prevented by an

upwardly extending link 88 connected at 90 with an ear extending forwardly from the forepart supporting plate 36. The upper ends of the links 84 and 88 are connected at 92, 94 with a U-shaped plate 96 the ends of which are connected to the pins 74. Thus it will be seen that the rubber sheets 58 which form the pressure applying pad member are confined in a box the shank and forepart portions having articulate side walls to permit the shank and forepart supporting plates to be adjusted in accordance with the longitudinal contour of the shoe bottom automatically in response to the application of pressure to a shoe on the pad.

The central portion of the pad member is covered by a flexible wire blanket 98 (Fig. 2) which bridges the shank supporting portion of the pad and extends toward the heel and toe ends, as shown herein. This blanket is illustrated as being similar to that shown in Letters Patent of the United States No. 2,497,195, granted February 14, 1950, on the joint application of N. S. Ferland and myself. As shown therein the blanket is formed of a plurality of transversely extending stiff metal rods or bars preferably formed of steel. These bars are hooked over flexible cables 100 to one end of each of which is secured a collar 102, the bars being held on the cables by clamping collars 104 secured to the opposite ends of the cables. The heel end of the pad is preferably covered by a steel plate 106 which provides a relatively rigid flat supporting surface for the heel end of the shoe. That portion of the blanket which underlies the toe end of the shoe is made more rigid lengthwise of the pad box than the metal blanket 98 but is designed to flex sufficiently to distribute the pressure properly around the bottom of the toe end of a shoe. For this purpose a plurality of flat relatively stiff metal strips 108 preferably formed of steel are secured to a rubber sheet 110 and extend radially from a point underlying the toe end of a shoe on the pad as shown in Fig. 2. The collars 102, 104 by which the metal bars of the blanket 98 are retained on the cables are provided with extensions 112 which overlie the adjacent portions of the members 106, 108 thus maintaining the various portions of the blanket in proper assembled relationship.

It will be noted that the upper portions of the walls 62 are formed with a flange 114 arranged to overlie the marginal portions of the heel end of the blanket to retain it in place and a similar flange 116 is formed on the plate 96 to overlie the forepart portions of the blanket. The links 72 are also provided with flanges 118 to overlie the margins of that portion of the blanket arranged to underlie the shank portion of a shoe. A shoe bottom-engaging surface is formed by a layer 120 of suitable material placed over the metal blanket and fitted between the upper layers of rubber sheets and the adjacent walls of the pad box. This layer of material may be formed of leather, polyethylene or any other suitable material.

In the operation of the machine a shoe is placed on the pad box and is substantially centrally located thereon as indicated in Fig. 1 whereupon pressure is applied to the shoe through the heel and toe abutments 18, 20. If the contour of the shoe bottom is different from that of the previous shoe operated upon the supporting members for the heel, shank and forepart will be adjusted as explained above until they correspond generally to the longitudinal contour of the shoe

bottom. It will be understood that the rubber sheets 58 forming the pad will assume corresponding shapes as will the flexible metal blanket 98 which, while it is relatively stiff transversely of the pad box has considerable lengthwise flexibility. As the pressure exerted on the shoe is increased the rubber of the lateral and lengthwise ribs of the sheets 58 will flow as required so that the pad will conform to the shape of the shoe bottom and a substantially uniform pressure will be applied around the marginal portions of the shoe through the metal blanket 98 as described more fully in Patent 2,497,195 referred to above. The metal plate 106 which underlies the heel end of the shoe insures that a substantially flat heel attaching surface will be formed and the radial plates 108 which underlie the forepart of the shoe provide sufficient rigidity at this end of the blanket while permitting it to conform to the contour of the shoe bottom at its toe end.

The articulate side walls at the shank and forepart portions of the pad box and the individual rubber sheets of which the pad is formed facilitate adjustment of the pad box in accordance with the contour of the shoe bottom.

Having thus described the invention what I claim as new and desire to secure by Letters Patent of the United States is:

1. In a machine for applying pressure to shoe bottoms, the combination of a pad for applying pressure to a sole and shoe, separate members for supporting the forepart, shank and heel portions of said pad, means mounting said heel-supporting member for heightwise adjustment, means mounting said shank and forepart-supporting members for tipping movements lengthwise of the pad, and means interconnecting said members for simultaneous heightwise and tipping movements respectively in response to the pressure of a shoe against said pad whereby the pad conforms generally to the longitudinal contour of the shoe bottom.

2. In a machine for applying pressure to shoe bottoms, the combination of a pad for applying pressure to a sole and shoe, said pad being composed of a plurality of layers of rubber capable of slipping one with respect to another, separate members for supporting the forepart, shank and heel portions of said pad, means interconnecting said members for simultaneous adjustments in response to the pressure of a shoe against said pad whereby the pad conforms generally to the longitudinal contour of the shoe bottom and relatively movable members engageable with the edge portions of the pad to maintain the layers in assembled relation while enabling relative movements of the layers during adjustments of said supporting members.

3. In a machine for applying pressure to shoe bottoms, the combination of a pad for applying pressure to a sole and shoe, said pad being composed of separate layers of rubber the underside of each layer having spaced parallel ribs and the upper side of each layer of rubber having spaced parallel ribs extending at right angles to the ribs on the undersides of the layers, separate members for supporting the forepart, shank and heel portions of said pad, and means interconnecting said members for simultaneous adjustments in response to the pressure of a shoe against said pad whereby the pad conforms generally to the longitudinal contour of the shoe bottom.

4. In a machine for applying pressure to shoe

bottoms, a pad box, the bottom of which is formed of pivotally connected members for supporting the heel, shank and forepart portions of a pad, side walls cooperating with said members to confine a pad supported by said members, the side walls of the shank and forepart portions being formed of a plurality of superposed rod-like members providing an articulate enclosure to facilitate relative tipping movements of the shank and forepart members, and a resilient pad within the box.

5. In a machine for applying pressure to shoe bottoms, a pad box, the bottom of which is formed of pivotally connected members for supporting the heel, shank and forepart portions of a pad, side walls cooperating with said members to confine a pad supported by said members, the side walls of the shank and forepart portions being formed of a plurality of superposed rod-like members providing an articulate enclosure to facilitate relative tipping movements of the shank and forepart members, and a resilient pad within the box, said pad comprising a plurality of sheets of rubber the opposite surfaces of each sheet being provided with spaced parallel ribs, the ribs on the upper faces extending in one direction and the ribs on the lower faces extending at right angles to the ribs on the upper faces.

6. In a machine for applying pressure to shoe bottoms, a pad box, the bottom of which is formed of pivotally connected members for supporting the heel, shank and forepart portions of a pad, side walls cooperating with said members to confine a pad supported by said members, the side walls of the shank and forepart portions being formed of a plurality of superposed rod-like members providing an articulate enclosure to facilitate relative tipping movements of the shank and forepart members, a resilient pad within the box, and means interconnecting said members whereby they assume approximately the longitudinal contour of the shoe bottom in response to the application of pressure through the pad to the bottom of the shoe.

7. In a machine for applying pressure to shoe bottoms, a supporting frame, a shank supporting member pivoted to said frame intermediate its front and rear edges, a gear segment attached to said supporting member and extending forwardly thereof, a forepart supporting member pivoted to the forward edge of said shank supporting member, a second gear segment meshing with the first named segment and pivoted to the forward portion of said frame, an arm connected to said second gear segment and extending forwardly from its pivot, and a pin and slot connection between said arm and the forward end of said forepart supporting member.

8. In a machine for applying pressure to shoe bottoms, a supporting frame, a shank supporting member pivoted to said frame intermediate its front and rear edges, a gear segment attached to said supporting member and extending forwardly thereof, a forepart supporting member pivoted to the forward edge of said shank supporting member, a second gear segment meshing with the first named segment and pivoted to the forward portion of said frame, an arm connected to said second gear segment and extending forwardly from its pivot, a pin and slot connection between said arm and the forward end of said forepart supporting member, a heel supporting member, and means connecting said heel supporting member and said shank supporting member whereby said heel supporting member moves

vertically in response to tipping movement of said shank supporting member.

9. In a machine for applying pressure to shoe bottoms, a supporting frame, a shank supporting member pivoted to said frame intermediate its front and rear edges, a gear segment attached to said supporting member and extending forwardly thereof, a forepart supporting member pivoted to the forward edge of said shank supporting member, a second gear segment meshing with the first named segment and pivoted to the forward portion of said frame, an arm connected to said second gear segment and extending forwardly from its pivot, a pin and slot connection between said arm and the forward end of said forepart supporting member, a heel supporting member, and means connecting said heel supporting member and said shank supporting member whereby said heel supporting member moves vertically in response to tipping movement of said shank supporting member, and a resilient pad carried by said supporting members, said pad comprising a plurality of layers of rubber each of said layers being provided with spaced parallel ribs on opposite sides thereof the ribs on one side extending at right angles to the ribs on the other side.

5

10

15

forward portion of said frame, an arm connected to said second gear segment and extending forwardly from its pivot, a pin and slot connection between said arm and the forward end of said forepart supporting member, a heel supporting member, means connecting said heel supporting member and said shank supporting member whereby said heel supporting member moves vertically in response to tipping movement of said shank supporting member, and a resilient pad carried by said supporting members, said pad comprising a plurality of layers of rubber each of said layers being provided with spaced parallel ribs on opposite sides thereof the ribs on one side extending at right angles to the ribs on the other side.

CHARLES K. WOODMAN.
